CLAIM

The ornamental design for a folding table, as shown and described.

DESCRIPTION

FIG. 1 is a front, right and top perspective view of a folding table, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a perspective view in a first state.

FIG. 10 is a perspective view in a second state.

FIG. 11 is a perspective view in a third state.

FIG. 12 is a perspective view in a fourth state; and,

FIG. 13 is a perspective view in a fifth state.

The broken lines depict portions of the folding table that form no part of the claimed design.

1 Claim, 13 Drawing Sheets
